UNITED STATES PATENT OFFICE.

HENRY K. HENNIGH, OF NEWCASTLE, INDIANA.

WINDMILL.

Application filed February 11, 1924. Serial No. 692,121.

To all whom it may concern:

Be it known that I, HENRY K. HENNIGH, a citizen of the United States, residing at Newcastle, in the county of Henry and State 5 of Indiana, have invented certain new and useful Improvements in Windmills, of which the following is a specification.

My said invention relatest to a wind mill and it is an object of the invention to provide a construction which shall utilize effectually the power of the wind and which at the inactive side of the mill shall offer as little resistance as possible to the wind.

Referring to the accompanying drawings, 15 which are made a part hereof and on which similar reference characters indicate similar parts,

Figure 1 is a perspective of my device,

Figure 2 is a side elevation with parts 20 broken away, and

Figure 3 a detail of certain parts of the framework on a larger scale.

In the drawings reference character 10 indicates a rotary post on which are supported 25 a plurality of vanes 11. Each of these vanes is carried on a horizontal bar 12 on which it is supported by means of a sleeve 13 forming part of the supporting frame of the vane, such frame being located at the 30 rear side of the vane. The remaining members 14, 15, 16 and 17 of each framework are held together by pipe joints and elbows as here shown or some other form of frame held together by different means may be 35 substituted if preferred. At the outer ends of the rods 12 I have shown devices 17' here illustrated as T-joints screw-threaded to sleeves 13 through which are threaded wires 18 connected at their upper ends to a cap 40 19 on the post 10.

Abutments may be provided for limiting the relative movement of oppositely located vanes such abutments being here shown as including horizontal pipe sections 20, vertical pipe sections 21 secured thereto by elbows and horizontal pipe sections 22 extending through four-way connections joining successive sections of the post 10, the sections 22 being secured to the sections 21 45 by T-joints or in any other desirable manner. The section 22 is loosely supported in the post so that the entire device can be moved by either one of the vanes at the ends of the corresponding rod 12.

50 The downward movement of each vane is limited by a rod 23 also mounted on the

post 10 and it will be evident that assuming the wind to be blowing in the direction of the arrow, the vanes will take the positions indicated in Figure 1 of the drawing. All 55 the vanes normally hang below the horizontal plane passing through their axes so that the wind may force them down into approximately vertical position as seen at the right-hand side of Figure 1 when in active position. At the same time the vane directly opposite is forced upward toward horizontal position by the wind and the action of the wind on the two vanes causes them to cooperate to move quickly into the desired 60 positions thereby maintaining each vane in its active position during the greatest possible arc of the circle traversed thereby in the operation of the windmill. The position of the intermediate vanes will be determined largely by gravity, the vane approaching the active position tending to fall 65 into an intermediate position and dragging the opposite vane out of active position toward an intermediate position. This action 70 on the part of the vanes approaching active position tends to bring them into the vertical position ready to receive the impact 75 of the wind with full effect.

The post 10 may be supported in any way 80 that will permit free rotation and ready transmission of power therefrom when used as a power generating device. In the present instance I have shown a sleeve 24 fixed 85 in supports 25 and 26 each of which may be 90 rigidly secured to a plurality of legs 27 by which the entire device is carried.

It will be obvious to those skilled in the art that various changes may be made in my device without departing from the scope of the invention and therefore I do not limit myself to the specific form shown in the drawings and described in the specification but only as indicated in the appended 95 claims.

Having thus fully described my said invention, what I claim as new and desire to secure by Letters Patent, is:

1. A wind mill comprising radially arranged horizontal vanes, a sleeve between them said sleeve being journaled coaxially with the vanes, and oppositely projecting fingers on the sleeve contacting with said vanes said fingers extending at an angle of approximately 90° to each other, substantially as set forth.

2. A wind mill comprising a post, a radial

series of independent pivots thereon, vanes on the pivots, and means pivoted on said pivots for holding opposite vanes spaced from each other at an angle of 90°, substantially as set forth.

3. A wind mill comprising a base, a radial series of independent pivots thereon, vanes on the pivots, and means pivoted on said pivots for holding opposite vanes spaced from each other at an angle of 90°, substantially as set forth.

4. A wind mill comprising a base, a radial series of independent pivots thereon, vanes independently mounted on the pivots, and pivoted means for spacing opposite vanes in planes approximately perpendicular to each other, substantially as set forth.

5. A wind mill comprising a post, rods extending through the post, pivots on each rod at opposite sides of the post, vanes car-

ried by said pivots, a sleeve about the rod extending through the post, and oppositely extending fingers on the sleeve adapted to engage the rear faces of the vanes, substantially as set forth.

6. A wind mill comprising a post, a rod extending through the post, pivots on the rod at opposite sides of the post, vanes carried by said pivots, a sleeve about the rod extending through the post, oppositely extending fingers on the sleeve adapted to engage the rear faces of the vanes, and fixed fingers below the rod for limiting the pivotal movement of the vanes, substantially as set forth.

In witness whereof, I have hereunto set my hand at Newcastle, Indiana, this 26th day of January, A. D. nineteen hundred and twenty-four.

HENRY K. HENNIGH.
